TO FOAMITE FIREFOAM COMPANY, OF NEW YORK, N. Y., A CORPORATION OF DELA-
WARE.

APPARATUS FOR EXTINGUISHING FIRES.

1,331,466.

Specification of Letters Patent. Patented Feb. 17, 1920.

Application filed February 23, 1917. Serial No. 150,301.

To all whom it may concern:

Be it known that we, ORLANDO R. ERWIN and CURTIS B. FLORY, citizens of the United States, residing at the city of Wauwatosa, county of Milwaukee, and State of Wisconsin, have invented new and useful Improvements in Apparatus for Extinguishing Fires, of which the following is a specification.

Our invention relates to manually controlled apparatus for generating foam for extinguishing fires, and it pertains more especially to that class of fire engines in which two normally separate chemical solutions are mixed to form foam which is forcibly discharged by its own expansion, upon the fire, when required.

The present greatly increased use of gasoline, oils, greases, etc., for automobiles, gasoline engines, motor boats, etc., and the consequent greatly increased fire hazard resulting therefrom has created a demand for reliable fire fighting apparatus of greater capacity than heretofore and which employs special fire extinguishing liquids or solutions.

The principal object of this invention is to provide simple, reliable and transportable apparatus of the foam generating type, which will not only be self contained, and manually controllable, but which will have greater fire extinguishing capacity than any devices heretofore known of like character for combating fires in highly inflammable liquids, etc.

Another object is to provide apparatus which will not only be entirely slop-proof during rapid transportation over rough roads, etc., to the fire, whereby any premature mixing of the solutions employed will be avoided and a portion of such chemicals lost, but which will be at all times manually controllable as to the pressures generated, and as to the velocity and quantity of foam discharged at the nozzle.

Further objects of the invention will be apparent hereinafter from the following specification and claims.

In the drawing:

The view which is partly in side elevation and partly in section, shows one form of our invention and illustrates a tank divided into two solution-containing compartments, said

tank being mounted on wheels for transportation purposes.

55

In the form of the invention shown in the drawing, a tank is mounted upon wheels E so that it may be transported from place to place. This tank is divided into two compartments C and D, intended to contain the normally separated solutions A and B, respectively, a handle G, or the equivalent thereof, being provided to draw the extinguisher from place to place.

One of the solutions comprises water, sodium bicarbonate and a foam forming substance such as saponin, and the other solution may be composed of water and aluminum sulfate, forming what is known as an acid solution. The letter H indicates a 65 valved mixing chamber, in the form of a relatively small cylindrical tank 8, into which the two solutions are simultaneously discharged, by gravity, through manually controlled discharge valves I and I' operatively connecting the chamber H with the compartments C and D respectively. This chamber H forms a mixing chamber, and when the solutions from the compartments C and D enter this chamber H through the 70 valved connections I and I', foam and gas are generated in the mixing chamber. The mixing chamber H is provided with a port 11 to which is connected the lower end of a vertical pipe 12. The upper end of this 75 pipe 12 is provided with a T cup 13 connected at one side with an elbow 14 in turn connected with a duct 16 leading to the compartment C and at its opposite side the T 13 is connected with an elbow 15, in turn connected to the duct 17 leading to the compartment D. This arrangement of pipe connections between the tank H and the compartments C and D serves to equalize the 80 pressures in the mixing chamber and the compartments thereby insuring a continuous discharge of the two solutions A and B into the mixing chamber when the valves I and I' are open. Removable covers M and 85 M' are provided on the top portions of the compartments C and D, respectively, to facilitate the filling, washing and inspection of such compartments.

95

100

105

A valve connection J' is connected to the bottom of the compartment C and a hose pipe K' leads from the valve connection J'

to the second mixing chamber H'. A similar valve connection J'' is connected with the bottom of the chamber D and from this connection J'' the hose pipe K'' also leads 5 to the chamber H'. Connected with the chamber H' is a discharge hose K terminating in a suitable nozzle L. Presuming the compartments to contain the solutions A and B, the operation of the device in the 10 case of fire, for example, is as follows:

The valves I and I' are first opened, thus permitting a portion of the two solutions A and B to flow by gravity into the foam chamber H wherein they are mingled and 15 foam and gas generated. The foam generated in this chamber H is forced by the pressure up through the pipe 12, the T 13, elbows 14 and 15 and ducts 16 and 17 into the chambers C and D, producing such pressure upon the solutions A and B still remaining in these compartments, that, when the valve connections J' and J'' are opened 20 the solutions will be forced out through these valves and through the hose lines K' and K'' into the second mixing chamber H' where they are thoroughly mixed, producing the fire extinguishing foam, which is forcibly ejected through the discharge hose K and the nozzle L so that the operator 25 holding the nozzle may play the stream of foam over or upon the burning surface for the purpose of extinguishing the fire.

It will be obvious that the essence of this invention is to produce simple fire extinguishing apparatus, in which not only the use of compressed air, or other exterior means, such as pumps, for forcing together the two, separated solutions is dispensed with, but in which the two solutions are 30 commingled and the resultant foam is forcibly discharged by the pressure of the gas generated which forms the foam, also that by the aid of throttle valves, controlling the solutions and foam, a uniform discharge at 35 the nozzle may be obtained, or otherwise controlled as required, entirely at the will of the operator, and further, that when in rapid transportation from place to place, the apparatus may be rendered slop-proof 40 (by closing the solution controlling valves), whereby any premature commingling of the 45

solutions is avoided, which results in corresponding loss of efficiency when the apparatus is required at the fire.

What we claim is:

55

1. In a fire extinguishing apparatus of the class described, the combination with a pair of compartments adapted to normally contain two separated foam producing solutions, a chamber for receiving and mixing 60 said solutions located in receiving connection with both compartments, means for simultaneously discharging said solutions into said mixing chamber where they are mixed, connections between said mixing 65 chamber and the compartments for conducting the resultant foam from the mixing chamber to said compartments above the solution levels in the compartments, a second mixing chamber, means connecting 70 each of the compartments with the second mixing chamber, and a discharge pipe connected with the said second mixing chamber.

2. In a fire extinguishing apparatus of the class described, the combination with a 75 pair of compartments adapted to normally contain two separated foam producing solutions, a mixing chamber for receiving and mixing said solutions located in receiving connection with both of said tanks, means 80 for simultaneously discharging said solutions together into said mixing chamber, ducts connecting said mixing chamber with the space above the solutions in said compartments for conducting the resultant foam 85 from said chamber to said compartments and above the solution levels of the latter, a second mixing chamber, a duct connecting each of said compartments with the second mixing chamber, a discharge outlet from the 90 second mixing chamber, and valve connections for manually controlling the admission and discharge of the foam to and from the mixing chambers.

In testimony whereof we affix our signatures in the presence of two witnesses.

ORLANDO R. ERWIN.
CURTIS B. FLORY.
